Primary Examiner — Jennifer Rivard

(57) **CLAIM**

The ornamental design for scalp and hairline protector, as shown and claimed.

DESCRIPTION

FIG. 1 is a perspective view of scalp and hairline protector showing my new design;
FIG. 2 is a front view thereof;
FIG. 3 is a back view thereof;
FIG. 4 is a side view thereof (opposite side is same image); and,
FIG. 5 is a top view thereof (opposite side is same image).
In FIGS. 2, 3 and 4, the broken lines represent stitching and form part of the claimed design.
